UNITED STATES PATENT OFFICE

102,874

DESIGN FOR A COMBINATION SALT AND PEPPER SHAKER

Delmar L. Callison, Coleman, Mich.

Application November 16, 1936, Serial No. 65,959

Term of patent 14 years

To all whom it may concern:

Be it known that I, Delmar L. Callison, a citizen of the United States, residing at Coleman, in the county of Mildand and State of Michigan, have invented a new, original, and ornamental Design for a Combination Salt and Pepper Shaker, of which the following is a specification, reference being had to the accompanying drawing, forming a part thereof.

In the drawing:

Fig. 1 is a perspective view of the article, showing my design.

Fig. 2 is a top plan view.

Fig. 3 is a bottom view.

What I claim is:

The ornamental design for a combination salt and pepper shaker, as shown.

DELMAR L. CALLISON.
